DESIGN.

—o—
J. L. FOLSOM.

CARPET.

No. 18,144.

Patented Mar. 6, 1888.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 18,144, dated March 6, 1888.

Application filed January 26, 1888. Serial No. 282,068. Term of patent 3½ years.

To all whom it may concern:

Be it known that I, JAMES L. FOLSOM, of Brooklyn, in the county of Kings and State of New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view 15 of a carpet showing my new design.

My design consists of a number of figures which are nearly square in general form and which are arranged in succession on a damask groundwork. These figures have a central 20 geometrical ornament in the shape of squares or crosses. The body of the figure around these

central ornaments is formed in some cases of a thick lattice-work made by crossing or intersecting lines, and in other cases by a mass of cross forms. The outline of these figures is 25 irregular, resembling coral formations. In the intervening spaces are less prominent forms of an irregular outline, resembling piles of block-work connected with and projecting from or joining the main figures. These figures are all arranged upon a ground of a damask character, formed by crossing or intersecting lines and small ornamental figures in the open spaces.

What I claim as new, and desire to secure 35 by Letters Patent, is—

The design for carpets, consisting of the design substantially as shown.

JAS. L. FOLSOM.
